UNITED STATES PATENT OFFICE.

HUGH McAFFEE, OF PITTSBURG, PENNSYLVANIA, ASSIGNOR TO CONSOLIDATED LAMP & GLASS CO., OF CORACOPOLIS, PENNSYLVANIA, A CORPORATION OF WEST VIRGINIA.

DESIGN FOR A SHADE.

40,895.

Specification for Design. Patented Sept. 20, 1910.

Application filed July 23, 1910. Serial No. 573,787. Term of patent 7 years.

To all whom it may concern:

Be it known that I, HUGH McAFFEE, a citizen of the United States, residing at Pittsburgh, in the county of Allegheny and State of Pennsylvania, have invented a new, original, and ornamental Design for Shades, of which the following is a specification, reference being had to the accompanying drawings, forming part thereof, in which—

Figure 1 is a side elevation of the design, and Fig. 2 is an inverted view of the design slightly in perspective.

This invention relates to a new, original and ornamental design for use in the decoration of shades in general, but more particularly for the ornamentation of electric light shades. It is also applicable to oil or gas lights and Welsbach burners in various forms of construction employing shades, and comprises, generally stated, the following characteristic features, reference being had to the drawings herewith.

The base or body of the shade herein

shown is pyriform or pear-shaped in outline, open at top and bottom, and provided with a converging end-flange or neck 1. Crossing the balance of shade and completely surrounding same, is the representation of a lattice or trellis 2 overlaid by a grape-vine pattern constituting an important feature of the complete design. At equidistant points upon said lattice or trellis are clusters of grapes 3 in relief depending toward the lower edge of said lattice; and, interposed between each two of said clusters, is a representation of grape leaves 4, 5 and 6, also in relief, arranged as most clearly shown by Fig. 1.

I claim:

The ornamental design for a shade, substantially as shown and described.

HUGH McAFFEE.
